GAS BURNER OR THE LIKE

Hervé Theunissen, Charleroi, Belgium

Application May 14, 1932, Serial No. 611,341
In Belgium August 6, 1931

3 Claims. (Cl. 158—109)

This invention relates to gas burners or the like.

A burner according to the invention is characterized in that the combustible gas is sucked inside a convergent truncated conical chamber by air which enters this chamber after it has been projected tangentially inside a cylindrical chamber surrounding the device for the admission of gas. The jet of gas is preferably introduced into the said chamber in the form of a divergent cone. The cylindrical and truncated convergent chambers may be followed by a divergent truncated conical chamber, which may be followed by a cylindrical chamber, at the end of which the mixture burns.

According to a modification of construction, the mixture is made to penetrate inside a nozzle where secondary air of combustion is admitted in a large number of jets of small diameter, arranged along a divergent truncated conical surface and perpendicularly to the latter surface.

The opening or openings for the admission of primary air inside the first mentioned cylindrical chamber may be adjusted so as to vary the thickness of the jet of air which is projected tangentially to the wall of the cylindrical chamber, without varying its width.

The means for adjusting the said thickness may consist of a relative displacement of two concentric cylindrical bodies provided with openings which are displaced upon each other.

The opening or openings for the admission of primary air is or are preferably cut bevel in the substance of the cylindrical body or bodies.

35 In the accompanying drawing:

Figures 1, 2, and 3 show, by way of example, one mode of carrying the invention into effect.

In the drawing:

Figure 1 is a longitudinal section of a burner according to the invention.

Figure 2 is a section made along the line 2—2 of Figure 1.

Figure 3 is a section made along the line 3—3 of Figure 1.

45 Referring to the drawing:

A tube 1 provided with a nozzle 13, which is made adjustable by means of a needle 14 for the injection of gas, opens axially into a convergent truncated conical chamber 3 which forms a prolongation of a cylindrical chamber 2.

The cylindrical chamber 2 is pierced with a rectangular port 7 leaving free passage from a nozzle 6, arranged tangentially on the cylinder 2, for the injection of the air.

55 The adjustment of the width of the port 7 is

effected by means of a drum 12 pierced with a hole 10 (see Fig. 2) having a cross-section identical to that of the port 7 and which may be superposed exactly on the latter.

The rotation of the drum 12 inside the cylindrical body 2 allows of varying the section for the admission of air by the relative position of the orifice 10 against the port 7 and of varying therefore the thickness of the jet of air which is projected tangentially against the inner wall 10 of the cylindrical chamber.

It is to be noted that whatever the adjustment of the opening may be, the cross-section for the passage of the air is always formed by a slot of constant width and variable height, 15 according to the position of the drum.

On the other hand, the port 7 and the orifice 10 are cut bevel in the substance, so as to produce for all the positions a tangential injection of the air into the annular space formed by the 20 cylindrical body of the burner and the tube of injection of combustible gas.

The rotation of the drum 12 inside the body 2 may be actuated from the outside by an Archimedean screw 15 acting upon a notched sector 25 16 secured to the drum, or by any other known device.

The convergent truncated conical portion 3 may be followed by a divergent truncated conical chamber 4 which may be followed by a 30 straight or curved conduit 5 intended to bring the mixture to the place of utilization.

The burner according to the invention may be also constructed as follows:

A nozzle is fixed to the end of the tube 5. 35

The nozzle consists of an outer casing 8 having the shape of a divergent truncated cone, fixed to the tube 5.

Concentrically inside the casing 8 is fixed a similar cone 9 made of refractory material or 40 the like, in such a manner as to leave an annular space 15 between the casing and the refractory cone.

The refractory cone is pierced along its entire surface and perpendicularly to the latter, with 45 many holes of small diameter permitting the injection of very finely divided air from the space 15 towards the inside of the cone.

The secondary air of combustion is brought into the peripheral space 15 through a tube 11 50 fixed tangentially upon the casing 8. The tangential arrangement of the tube has for its object to facilitate an even distribution of the pressure upon all the injection holes.

The nozzle 8 is used in the case of a two-phase

combustion that is when the whole of the air of combustion is not injected into the burner proper. In this case, the additional amount of air is brought through the tube 11 into the annular space 15 at the working pressure and is blown through the refractory cone into the mixture delivered by the tube 5.

At the outlet of tube 5, without the nozzle 8, the mixture would spread along a cone owing to 10 the strong rotary motion which is imparted to it by the cyclone of air.

This centrifugal motion will have for its effect to develop the primary mixture along a helicoidal sheet against the refractory cone, which sheet is 15 cut in a perpendicular direction by the jets of secondary air.

The nozzle device 8, added to the burner described, permits of obtaining almost instantaneously a perfectly homogeneous mixture.

20 The working of the burner according to the invention is as follows:

The combustible gas is introduced into the cylindrical chamber 12 through the nozzle 1, the needle 14 and mouthpiece 13 of which, spread the 25 jet in the form of a divergent cone.

It is to be noted that this effect may be obtained by any other known nozzle constructions.

The exit speed and the quantity of gas delivered 30 by the nozzle 1 depend on the opening of the needle and on the pressure of admission of the gas.

The air of combustion is injected into the chamber 12 tangentially to the inner wall thereof and has a more or less rapid rotary motion, according 35 to its initial pressure. That is, for any quantity delivered by the nozzle 1, therefore for any predetermined consumption, the device enables to vary the speed of the cyclone of air by suitably modifying the pressure of admission and the 40 amount of air delivered for a given pressure, by acting upon the opening of the port 7.

The peripheral speed of the air is increased according as it advances into the convergent conical chamber where it causes, by its intense centrifugal motion, a suction of the cone of gas from the nozzle 1. The two fluids are intermixed intensely and the mixture penetrates into the cone 4 which sends the mixture, which still has an intense rotary motion, into the conduit 5 at the outlet of 50 which it may be allowed to burn, or it may be sent into the nozzle 8 to meet secondary air as above described.

The advantages of the present burner are as follows:

55 1. It permits of obtaining a perfect mixture of the combustible gas and of the air of combustion.

This allows of obtaining higher temperatures.

2. The burner may work with different quantities of mixture without appreciable variation of the temperature of combustion.

Indeed, for a pre-determined equilibrium temperature, the suitable proportion of combustion air for each gas delivery of the nozzle 1 is obtained by regulating the port 7. If the pressure of the fan is not modified, the pressure of admission of the air into the cylinder and consequently the rotary motion will remain the same, so that whatever its delivery may be, the burner 65 will work with the same two factors: namely same proportion of gas in the mixture and same rotary speed of the mixture.

Since for a gas of given calorific power, the 70 temperature of combustion results from the said two factors, the burner will consequently be able

to work with different outputs and retain the same temperature of combustion of the mixture.

3. Inversely, the same burner allows of obtaining a very large scale of temperatures for the same quantity delivered.

It is indeed possible by keeping constant the gas delivery of the gas nozzle, to modify within very wide limits, the speed of injection of the air of combustion by adjusting the pressure of the fan for each opening so as to keep constant the 10 amount of air introduced.

4. From the advantages 2 and 3 combined together, it results that one type of burner may be used within extremely wide limits of temperature and deliveries without reducing the efficiency of combustion.

5. The intense rotary motion imparted to the mixture in the burner has for its effect to produce at the outlet of the conduit 5 a dispersion of this mixture along a divergent cone, the opposite of 20 what is obtained with ordinary burners, the flame of which has generally the shape of a convergent cone.

This effect is appreciable and has obvious advantages for the heating of reaction chambers 25 of ovens or of combustion chambers and avoids the well known drawbacks of the converging blow-flame.

6. In the case of a two-phase combustion, that is: (1) partial injection of the combustion air 30 in the burner (primary air) (2) supplementary injection of air into the mixture at the outlet from the burner (secondary air), which is very often necessary in metallurgical or other heat treatments, a divergent mixing cone at the outlet from 35 the burner permits of injecting secondary air under much more efficient conditions.

7. Owing to the fact that the speed of the rotary motion of the mixture may be increased to a large extent, the burner permits of utilizing 40 very rich gases without the danger of back-fire, by the simple adaptation of the speed of injection of the primary air to the speed of propagation of the flame of the mixture.

8. On the other hand, thanks to the perfect 45 homogeneousness of the mixture effected in the burner, the latter gives the possibility of utilizing very poor gases without the risk of extinction.

This nozzle 8 gives the following additional advantages:

(1) it allows of obtaining an atmosphere practically without visible flame at the outlet of the nozzle with all the advantages given by such a kind of combustion: homogeneousness of the 55 heating (the oxidation of the substance to be heated being reduced to a minimum), precision of thermal treatments, etc.

(2) the use of the nozzle 8 affords the faculty of using as secondary injection, air which has 60 been previously used with all the advantages resulting therefrom, either from the point of view of the possibility of recovering the lost heat, or for obtaining high temperatures, or with a view to utilization of gas with very small calorific 65 power.

(3) possibility of heating in a uniform manner chambers of large volume.

I claim:

1. A gas burner having a cylindrical chamber 70 connected to a convergent truncated conical chamber, the latter being connected to a divergent truncated conical chamber, means for admitting air tangentially inside the cylindrical chamber, means for admitting gas inside the 75

convergent truncated conical chamber, and means for admitting air through a plurality of small jets perpendicular to the surface of the divergent truncated conical chamber.

- 5 2. A gas burner having a cylindrical chamber connected to a truncated convergent conical chamber the latter being connected to a divergent truncated conical chamber, means for admitting air tangentially inside the cylindrical chamber 10 through an opening having its sides cut bevel towards the inner wall of the cylindrical chamber, means for admitting gas inside the convergent truncated conical chamber, and means for admitting air through a plurality of small jets perpendicular to the surface of the divergent truncated conical chamber. 15
- 10 3. In a gas burner having a cylindrical chamber, means for admitting air under pressure in a gyratory motion in the cylindrical chamber, means

arranged adjacent the peripheral wall of the cylinder chamber for regulating the air admitted in the cylindrical chamber, a truncated conical chamber connected to the cylindrical chamber and sharply convergent so as to strongly accelerate the gyratory motion of the air, a divergent mixing chamber connected to the truncated conical chamber, means arranged centrally through the cylindrical chamber for admitting combustible gas axially at the entrance of the convergent truncated conical chamber, and means for regulating the gas delivery at the entrance of the truncated conical chamber, whereby the air admitted into the cylindrical chamber about the gas admission means independently insures of 15 the sucking of the gas into the truncated conical chamber and the production of an intimate mixture of gas and air.

HERVÉ THEUNISSEN.
